UNITED STATES PATENT OFFICE

GIUSEPPE GISOLFI, OF BROOKLYN, NEW YORK

DESIGN FOR AN ANCHOR FOR NIGHT CANDLES

Application filed September 10, 1929. Serial No. 32,718. Term of patent 14 years.

To all whom it may concern:

Be it known that I, GIUSEPPE GISOLFI, a citizen of the United States, residing in New York city, borough of Brooklyn, in the county of Kings and State of New York, have invented a new, original, and ornamental Design for Anchor for Night Candles, of which the following is a specification, reference being had to the accompanying drawings, forming a part thereof, and of which—

Figure 1 is a perspective view showing my new design as applied to a candle; Figs. 2 and 3 are bottom and edge views thereof.

I claim:

The ornamental design for an anchor for night candles as shown.

GIUSEPPE GISOLFI.
